UNITED STATES PATENT OFFICE.

HAMILTON C. BATES, OF CHESTER, CONNECTICUT.

NAIL-BUFFER.

1,023,915.

Specification of Letters Patent. Patented Apr. 23, 1912.

Application filed April 19, 1911. Serial No. 622,128.

To all whom it may concern:

Be it known that I, HAMILTON C. BATES, citizen of the United States, residing at Chester, in the county of Middlesex and 5 State of Connecticut, have invented certain new and useful Improvements in Nail-Buffers, of which the following is a specification.

The object of my invention is to provide 10 a device of the class specified, which has features of novelty and advantage.

Figure 1 is a lateral view of the customary nail buffer. Fig. 2 is a lateral view 15 of the band adapted to secure an extra polishing cover. Fig. 3 is a cross sectional view with band in place. Fig. 4 is a cross sectional modification of said band. Fig. 5 is a lateral view of all the parts assembled. Fig. 6 is a plan view of Fig. 5.

20 Referring to the drawings the buffer —1— is the customary buffer preferably soft and resilient having a handle —2— secured to the face of the buffer-top —3— which face is preferably slightly curved 25 from end to end. The polishing surface —4— of the customary buffer is made of chamois, and soon becomes soiled or hard with usage.

I provide an extra polishing material 30 —5— preferably of chamois, which is adapted to fit over the chamois on the buffer. Said extra chamois is secured in place by an endless band —6— preferably made of metal, which is slid up over said chamois. 35 The upper edge of said band as at —7— when in place extends outside of the top —3— of the buffer, conforms in shape with said top and snugly fits outside of the buffer-top, being flush with the face thereof, that 40 is, flush with the top of the buffer top —3—. The band —6— is contracted toward its lower edge, so that said lower edge as at —8— tightly grips the extra chamois cover and securely holds the same in place. My 45 band —6— may be tapering in cross-section so that it has an inside flat surface, or have a contracted lower edge, as shown in the

modification of the same in Fig. 4 of the drawings so that while the lower edge of the band tightly grips the extra chamois 50 cover, the top edge of the band may slide up outside of the buffer top, and while it is being slid up outside of the buffer top, the extra chamois cover is at the same time being drawn tighter. 55

It will be noticed that the band —6— is curved from one end to the other, so that it has a slight spring action, which assists in holding the band and extra chamois cover in place. 60

By the term—curved from one end to the other—it is meant that the two sides of the endless band —6— are curved upward in the center thereof. The results of this band —6— being thus curved upward are that 65 when the band is being slid over the buffer, one presses up on the ends of the band so that the space within the band is enlarged, so that the band slips easier onto the buffer. This curved feature allows a continual 70 spring action to hold the extra chamois in place on the buffer as soon as one releases his fingers from the ends of the band. An especial advantage of a band of this construction is that the edge of the extra chamois 75 is entirely covered, and when my band is in place on the buffer, there are no rough surfaces whatever exposed on the buffer, which would catch or tear the finger-nails of the user. 80

I claim as my invention:

1. In a nail buffer, a removable polishing cover, a band having its upper edge extending outside of, and conforming in shape to, and flush with the face of the buffer-top, 85 said band being curved upward in the center thereof to allow a slight spring action, whereby said band and polishing cover are tightly held in place.

2. In a nail buffer, a removable polishing 90 cover, a band having its upper edge extending outside of, and conforming in shape to, and flush with the face of the buffer-top, said band tapering in cross section toward

the lower edge thereof and being curved upward in the center thereof to allow a spring action to said band.

3. In a nail buffer, a removable polishing cover, an endless band having a contracted lower edge, said band being curved upward in the center thereof and having a continual spring action whereby the lower edge

of the band is held embedded in said polishing cover in the position desired. 10

In testimony whereof I affix my signature in presence of two witnesses.

HAMILTON C. BATES.
